UNITED STATES PATENT OFFICE.

PANKRACY WASYLOWICH, OF CHELSEA, MASSACHUSETTS.

SOLDIER'S PROTECTOR.

1,274,645.

Specification of Letters Patent. Patented Aug. 6, 1918.

Application filed June 1, 1918. Serial No. 237,750.

To all whom it may concern:

Be it known that I, PANKRACY WASYLOWICH, a subject of the Emperor of Austria, residing at Chelsea, in the county of Suffolk and State of Massachusetts, have invented certain new and useful Improvements in Soldiers' Protectors, of which the following is a specification.

The primary object of the invention is 10 the provision of a protector adapted to be either worn by a soldier or moved from place to place by the soldier ready for immediate use when required, provisions being made for stopping and cushioning the bullets of the enemy as well as holding the same in a harmless position.

A further object of the device is to provide a protector that renders the bullets of the enemy entirely harmless to the soldier 20 in charge of the device although the soldier may readily fire upon the enemy without exposing himself or being seen from the enemy's lines, the device presenting an appearance calculated to deceive the enemy 25 into believing that the same is something else than a bullet shield.

In the drawings forming a part of this application and in which like reference characters designate corresponding parts 30 throughout the same,

Figure 1 is a side elevation of the device set up for use with the soldier, represented by dotted lines, firing therethrough;

Fig. 2 is a rear elevation of the device; 35 Fig. 3 is a horizontal transverse sectional view taken upon line III—III of Fig. 2;

Fig. 4 is a perspective view of the device provided with means for suspending the same from the body of the soldier; and

Fig. 5 is an enlarged horizontal sectional view through the side of the device through which the firing takes place.

My invention is in the nature of a bullet-proof guard or barrier and may be constructed of any desired size being herein illustrated for carrying by the soldier as well as for wheeling about as desired.

A base plate 10 is provided preferably 45 formed of bullet-proof material, such as suitable metal, the same having a cushion form of covering 11 preferably of leather. A second leather covering 12 is carried by the plate 10 separated from the covering 11 by means of a plurality of springs 13 while successive layers 14, 15 and 16 of cotton, hair and cotton respectively, are positioned

inwardly of the covering 12. A plurality of springs 17 are interposed between the plate 10 and a metallic screen or mesh member 18 upon the inner face of the inner cotton layer 16. 60

Strengthening ribs 19 are positioned upon the rear face of the plate 10, while the marginal rim or flange 20 extends entirely around the plate. A brush-work of wooden bristles 21 is carried by the leather covering 11 and these bristles being thickly positioned upon said outer covering form ready means for stopping bullets as well as resisting any bayonet attacks. The outer leather covering 11 is secured to the flange 20 by means of a metallic binding strip 22. 70

The plate 10 is provided with a notch or slot 23 in one side thereof adapted to accommodate a rifle for positioning therethrough in firing upon the enemy. The outer covering 11 is carried around the edges of this slot 23 by means of a supplemental piece or strip 24 and the bristles 21 being omitted from the strip 24, permits such a rifle such as indicated at 25 by dotted lines in Fig. 1 to be readily thrust through the device by the soldier such as 26 positioned therebehind. Wheels 27 are preferably mounted at a point adjacent one end of the plate 10 by means of an axle 28 journaled in bearings 29 upon the said plate with recesses 30 formed in the plate to receive the wheels. Curved handles 31 are provided adjacent the opposite end of the plate 10 90 for employent in pushing or pulling the device over the ground such as 32, when desired to transfer the same from one place to another. The end 33 of the device which is adjacent the wheels 27 is squared or flat 95 for seating upon the ground with the plate 10 supported thereby and by the wheels 27 in its upright operative position. The opposite or upper end 34 of the device is curved and the appearance of the structure forwardly thereof as viewed by the enemy is that of a brush or grain pile as only the wooden bristles 21 are visible. The soldier 26 positioned behind the plate 10 100 may readily fire upon the enemy through the side slot 23 without being observed, while the bullets of the enemy will be stopped by the bristles 21 and the springs 13 and 17 cushioning the impact of the bullets upon the plate 10. The leather layers 11 and 12 as well as the inner layers 14, 15 and 16 110 also cushion the bullets of the enemy as

well as assist to prevent the bullets from passing through the device, although the rear plate 10 is also designed for this purpose.

5 The wheeled form of the invention illustrated in Figs. 1 and 2 of the drawings is serviceable for foot soles while the same protecting device is shown in Fig. 4 having a strap 35 for attaching the device to the 10 shoulders of a soldier for readily carrying the same while a bracket 36 having straps 37 is also provided to be secured to the waist of the soldier. When the bracket 36 and straps 37 are secured to the soldier's waist, 15 the device with the plate 10 is spaced slightly forwardly of the soldier, while the strap 35 being loosely positioned around the soldier's shoulders or neck suitably spaces the device forwardly of the wearer for permitting 20 the soldier to shoot through the side slot 23. The straps 35 and bracket 36 may be also employed for securing the device to a saddle for carrying upon a horse by the cavalry and will be seen that a bullet 25 protector is provided which protects the user from being discovered as well as being hit by the enemy.

What I claim as new is:—

1. A portable bullet protector comprising 30 a plate having a side slot, spaced outer leather coverings upon said plate, springs between said coverings, a plurality of layers of bullet stopping material inwardly of said layers, springs secured between said plate

and layers and wood fiber bristles thickly 3 provided upon the outer face of said outer coverings adapted for misleading the enemy as to the presence of said bullet protecting means.

2. In combination with a bullet-proof 4 plate, reinforcing ribs upon said plate, a marginal flange upon the plate, an outer leather covering secured to said flange, a thick covering of wooden bristles projecting 4 from said covering, the said bristles, covering and plate having an interrupted side portion adapted for receiving a firearm during the operation of the device.

3. In combination with a bullet-proof plate, reinforcing ribs upon said plate, a marginal flange upon the plate, an outer leather covering secured to said flange, a thick covering of wooden bristles projecting from said covering, the said bristles, covering and plate having an interrupted 5 side portion adapted for receiving a fire arm during the operation of the device, a leather layer covering spaced inwardly of said outer covering, springs between said covering, hair and cotton layers positioned 6 inwardly of said inner leather covering, a metallic mesh provided inwardly of said innermost layer, springs interposed between the said mesh and plate, and transferring means for the device attached to said plate. 6

In testimony whereof I affix my signature.

PANKRACY WASYLOWICH.
